SYSTEM FOR REMOVING CRANKCASE
VAPORSJohn S. Fluor, Jr., Santa Ana, Calif., assignor to
The Fluor Corporation, Ltd., Los Angeles,
Calif., a corporation of California

Application March 17, 1937, Serial No. 131,356

7 Claims. (Cl. 123—196)

This invention has for its general object to provide a system for removing vapors and gases from the crank case of an internal combustion engine. Tests have indicated that by continuously removing crank case vapors during engine operation, oil contamination over a period of time by dilution, as well as by sludge and gum formation due to oxidation, are materially reduced as compared with the degree and kind of oil contamination that normally occurs. By communicating a depression to the vapor space in the crank case, I remove condensable vapors that would otherwise dilute the oil by dissolving therein or condensing on the walls of the crank case, and I also produce in the vapor space a less oxidizing atmosphere that inhibits the formation of contaminating gums and sludges.

In accordance with the invention, vapors are continuously removed from the crank case during engine operation through a conduit communicating with the vapor space. Preferably, the engine exhaust gas flow is utilized to produce a depression or suction acting to draw the crank case vapors through the conduit, as by connecting the latter to a jacket surrounding and spaced from the exhaust pipe to form a passage within which a draft is induced by the discharge of gases from the exhaust pipe. For the purpose of illustrating a typical embodiment of the invention, it is herein shown and described in conjunction with an engine manifold and exhaust pipe cooling system that itself comprises the subject matter of my copending application, Ser. No. 102,878, filed September 28, 1936 of which this application is a continuation-in-part. Although the crank case vapor removal and manifold and exhaust pipe cooling systems may advantageously be combined in one installation, it is to be understood that the present invention is to be regarded broadly as independent of the manifold and exhaust pipe cooling system, except as to its claims in which the two systems are claimed in combination. Also it may be observed that the invention is applicable to internal combustion engines generally, including stationary engines and automotive vehicle engines.

The above mentioned objects, as well as additional features of the invention will be more fully understood from the following detailed description, throughout which reference is made to the accompanying drawing, in which:

Fig. 1 is a general view, partly in section, showing the invention as applied to an automotive engine;

Fig. 2 illustrates a variant form of the invention as applied to a stationary engine; and

Fig. 3 is an enlarged fragmentary view showing the suction conduit and condensate drain tube connection at the crank case oil inlet.

In Fig. 1 of the drawing, I have shown a conventional vehicle chassis including the engine 10 mounted on side rails 11, and the body or cab having a vertically extending wall 12 at the rear of the engine, and floor boards 13. The drawing shows a water cooled engine having hose connection 14 with the radiator 15, and the usual fan 16 which directs a current of air longitudinally of the exhaust manifold 17 toward the mouth 18 of the exhaust pipe jacket 19. The exhaust pipe 20 and muffler 21 are jacketed by pipe 19 and shell 22 having a tail pipe 23 projecting beyond the muffler outlet 24, said pipe and shell being annularly spaced from the exhaust pipe and muffler to form a passage 25 through which an induced flow of air is created by virtue of the exhaust gas discharge from the muffler outlet. It should be mentioned that in the claims, the term "exhaust pipe" is to be construed broadly as including both the pipe proper that connects with the exhaust manifold, and the muffler, except as to those claims where the parts are separately specified.

During engine operation, the warm air in the vicinity of the exhaust manifold 17 is directed rearwardly along the manifold by the fan 16, and is drawn into the mouth 18 of the exhaust pipe jacket to be discharged with the exhaust gases from the tail pipe 23. With the warm air thus being immediately and continuously removed from the engine, overheating of such engine parts as the fuel pump 26 and fuel line 27 leading to the carburetor 28, is effectively avoided. By removing the engine heat in this manner, and also by heat insulating the exhaust pipe by the air jacket, I reduce the heat transference to walls 12 and 13 of the body to the extent that the interior thereof will at all times remain comparatively cool.

The invention is more particularly concerned with the provision of means, generally indicated at 29, for removing vapors from the engine crank case 10a. The vapors are withdrawn through a conduit 30 communicating with the vapor space in the crank case by suitable connection therewith, for example by a removable attachment 31 with the usual breather cap 32 applied to the oil inlet 33. The opposite end of the conduit may connect with the exhaust pipe jacket at any suitable point, typically, as illus-

trated, by a connection at 34 with the end of shell 22. As will be apparent, the depression existing in passage 25 by virtue of the exhaust gas discharge, acts during engine operation to continuously withdraw vapors from the crank case 40a through line 30. Preferably the communication of suction from the suction passage to the crank case will be controllable, as by means of a suitable valve 36 in pipe 30. Loss of oil from the crank case by entrainment in the withdrawn vapor stream may be prevented by installing a suitable filter or separator 53 in line 30, any oil arrested by the filter being permitted to drain back through the line into the crank case.

15 The variant form of the invention shown in Fig. 2 is similar to the described form, except that here the air jacket and crank case vapor withdrawal conduit are shown applied to a stationary engine having an overheated exhaust.

20 As in the previous instance, warm air is drawn from the exhaust manifold 17 into the mouth 37 of jacket 38 placed about the vertically extending exhaust pipe 39 and connecting with shell 40 placed about the muffler, not shown, as in Fig. 1.

25 Conduit 41, connected to the muffler jacket as in Fig. 1, has an attachment generally indicated at 42 with the crank case oil inlet 43, as shown in detail in Fig. 3. This connection comprises a nipple 44 containing an internal annular flange 45 forming a pocket 46 into which any liquid deposited in pipe 41, as by condensation of vapors being withdrawn from the crank case, drains from the lower swaged end 47 of nipple 48. The connection at 42 may be broken to permit pipe 41 and the nipple 48 to be moved to one side when the crank case is to be filled through opening 43, by raising sleeve 49 which is normally slipped down over nipple 44. Condensate draining into pocket 46 is withdrawn through a drain tube 50 extending through a vertical slot 51 in the sleeve 49.

I claim:

1. In combination with an internal combustion engine having an exhaust pipe and oil containing crank case, a jacket surrounding said exhaust pipe and containing a passage within which a depression is created by virtue of the engine exhaust gas flow, and a conduit connecting said passage with the vapor space in said crank case.

45 2. In combination with an internal combustion engine having an exhaust pipe connected to a

muffler, and an oil containing crank case; a jacket surrounding said muffler and containing a passage within which a depression is created by virtue of the engine exhaust gas flow, and a conduit connecting said passage with the vapor space in 5 said crank case.

3. In an engine driven vehicle, the combination comprising an internal combustion engine having an exhaust pipe and an oil containing crank case, a conduit connected with the vapor space in said 10 crank case, and means for communicating suction to said space through said conduit by virtue of the engine exhaust gas flow to draw vapors from said space into the exhaust gas stream.

4. In combination with an internal combustion 15 engine having an exhaust manifold and an oil containing crank case, a conduit positioned to receive heated air directly from said manifold, means for drawing the heated air through said conduit by virtue of the engine exhaust gas flow, 20 and means connecting said conduit with the vapor space in said crank case whereby vapors are drawn from said space into said conduit.

5. In combination with an internal combustion engine having an exhaust manifold, an exhaust 25 pipe and an oil containing crank case; a conduit surrounding and spaced from said exhaust pipe and having an inlet positioned to receive heated air directly from said manifold, such heated air being drawn through said conduit by virtue of 30 the engine exhaust gas flow, and means connecting said conduit with the vapor space in said crank case.

6. In combination with an internal combustion engine having an exhaust pipe and oil containing 35 crank case, a conduit connected with the vapor space in said crank case, and means operating by virtue of the exhaust gas flow to communicate lowered pressure through said conduit to the crank case to draw vapors from said space. 40

7. In combination with an internal combustion engine having an exhaust pipe and oil containing crank case, a conduit connected with the vapor space in said crank case, means operating by virtue of the exhaust gas flow to communicate lowered pressure through said conduit to the crank case to draw vapors from said space, and means for controlling the withdrawal of vapors through the conduit independently of the exhaust gas flow. 45
